UNITED STATES PATENT OFFICE.

PAUL SATTELKAU AND HENRY DOMBRINK, OF OAKLAND, CALIFORNIA.

PROCESS OF PRODUCING HOLLOW OBJECTS OF PLASTIC MATERIAL.

1,288,214.

Specification of Letters Patent.

Patented Dec. 17, 1918.

Application filed November 3, 1917. Serial No. 200,051.

To all whom it may concern:

Be it known that we, PAUL SATTELKAU and HENRY DOMBRINK, citizens of the United States, residing at Oakland, in the 5 county of Alameda, State of California, have invented a new and useful Process of Producing Hollow Objects of Plastic Material, of which the following is a specification in such full and clear terms as will enable 10 those skilled in the art to construct and use the same.

This invention relates to a cement pipe and the process of manufacturing same, and its object is to produce an exceedingly 15 strong and dense pipe capable of withstanding considerable pressures without leakage.

An object of the invention is to produce a cement pipe which will contain the minimum of moisture at the time the cement sets 20 as well as the minimum of interstitial spaces containing occluded air.

In the drawing, there is illustrated a form of machine capable of producing the pipe by the process herein outlined.

25 While the term "cement" has been used herein for convenience in explanation, it will be understood that this pipe may be made of any plastic material capable of being handled in the manner of cement, and which 30 will set quickly enough to make it commercially valuable for the purposes herein disclosed.

Other objects of the invention will appear as the description proceeds.

35 An embodiment of the invention is shown in the drawings in which the same reference numeral is applied to the same portion throughout, but we are aware that there may be modifications thereof.

40 Figure 1 is a side elevation of the complete apparatus,

Fig. 2 is a vertical sectional view of the apparatus on the line 2—2, Fig. 1, looking in the direction of the arrows, and

45 Fig. 3 is an end view of a section of pipe having steel reinforcing therein.

The numeral 1 indicates a suitable journaled post, 2 is a similar post, which posts have removable bearing caps 3 and 4. The 50 apparatus comprises a tube formed of three sections 5, 6 and 7, each of which has flanges, as indicated at 8 to 12 inclusive, for securing the several parts of the tube together. Bolts 13, in such numbers as may be desired, 55 are used to connect the parts of the tube, and, after being connected together, caps

14 and 15 are screwed on the ends of the segments forming the tube. The cap 15 has a trunnion 16 which rests in the bearing at the top of the post 1. The cap 14 has a hollow trunnion 17 which rests in the bearing 60 at the top of the post 2.

The shaft 17 has a pipe 18 inserted in the opening therethrough, and a valve 19 permits the air to be exhausted from the tube 65 formed by the segments 5 to 7 inclusive. A pulley 20 is mounted on the shaft 17, and it is driven at a high rate of speed from a belt 21 leading to another pulley 22, which receives its power from any suitable source. 70

In order to prevent the tube from wabbling during the time the cement is being poured therein, the segments are provided with the circumferentially extending track 23, 24 and 25, the latter parts making up 75 a complete circle and resting upon bearing rollers 27, 28; the former carried in a bearing block 29, while the latter is carried in the lower portion of a post 30 which extends above the tube. This post has a movable 80 arm 31 at its upper end, which arm carries a roller 32 bearing on the top of the ring surrounding the tube, and it may be removed from contact with said ring by releasing the pressure of a screw 36, which extends into 85 the top of the post 30, said screw having an operating hand wheel 37.

The operation of manufacturing the pipe is as follows:

A charge of the plastic material, of which 90 the pipe is to be made in order to produce a pipe of the desired thickness, is placed within the tubular member, the cap 15 being in place to prevent the escape of said material from the tube. The cap 14 is then 95 placed in position and the tube is mounted for rotation in the bearing 1 and 2. At that time or during the progress of the rotation of the tube, whatever air may be within the tube is withdrawn therefrom through the 100 pipe 18, whereupon the valve 19 is closed and the tube is rapidly rotated for such a length of time as experience determines is necessary to cause the plastic material to be evenly distributed throughout the length of 105 the tube, and to set sufficiently to be self-sustaining.

After the plastic material has assumed the position shown in Fig. 2, and has been rotated for such a length of time as is required 110 to make it self-sustaining, the tube may be removed from its supports and set away

for such a length of time as is necessary to permit the plastic material to harden enough to allow the removal of the segments 5 to 7 inclusive therefrom.

5 It will be clear that a plastic material pipe, such as 39, in which no reinforcing is used, may be produced, or a pipe such as the pipe 40 may be produced in which such an amount of circumferential reinforcing 10 41 and longitudinal reinforcing 42 to 44 inclusive may be used as good practice and engineering requires or demands for the particular pipe to be made.

It will be clear to those skilled in the art 15 that by increasing the vacuum within the mold to the highest practicable point that any bubbles of air contained within the mass of plastic material will be completely removed therefrom and the plastic material 20 will, by reason of such removal of air bubbles, solidify much denser than would be the case if such bubbles were allowed to remain therein.

Having thus described our invention what we claim as new and desire to secure by Letters Patent of the United States is as follows, express reservations being made of permissible modifications.

A process of producing hollow objects from plastic material which consists in 25 charging a receptacle with a quantity of plastic material, reducing the air pressure within the receptacle below atmospheric, rapidly rotating the receptacle, until the plastic material therein forms a shell on the 30 inside of the cylinder, continuing the rotation until the material has set sufficiently to be self-sustaining, discontinuing the rotation, and then removing the receptacle from the hollow object produced.

40 In testimony whereof we have hereunto set our hands this 8th day of October A. D., 1917.

PAUL SATTELKAU.
HENRY DOMBRINK.
